UNITED STATES PATENT OFFICE.

GEORGE E. ALTMANN, OF WASHINGTON, DISTRICT OF COLUMBIA.

DRIP-PAN ALARM.

Application filed September 11, 1922. Serial No. 587,368.

To all whom it may concern:

Be it known that I, GEORGE E. ALTMANN, a citizen of the United States, residing at Washington, in the District of Columbia, have invented a new and useful Drip-Pan Alarm; and I do hereby declare the following to be a full, clear, and exact description of the invention, such as will enable others skilled in the art to which it appertains to make and use the same.

The invention relates to drip pan alarms, and has for its object to provide a device of this character which may be easily and quickly attached to the side flange of a drip pan under an ice box, and controlled by a float disposed within the pan. The float controlling a spring motor which actuates a bell ringing device when released by the pulley.

A further object is to provide the float with a chamber having its lower end open, and in which chamber the air is compressed as the water level in the pan rises, thereby increasing the buoyancy of the float and assuring the release of the spring motor.

A further object is to dispose the spring motor within a casing, one end of which is detachably connected to the pan and the casing forming a sounding device against which the bell flapper engages during its oscillation under the influence of the spring motor.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a top plan view of the device, the casing being broken away to better show the structure, and showing the same supported on a flange of a portion of a drip pan.

Figure 2 is a vertical longitudinal sectional view through the alarm device and a portion of the pan, taken on line 2—2 of Figure 1.

Referring to the drawing, the numeral 1 designates a portion of a conventional form of drip pan adapted to be disposed below the discharge end of the drain pipe of an ice box, into which water from the ice compart-

ment of the ice box drains. It has been found that unless considerable attention is paid to the drip pan, the same will overflow and consequently involve a considerable amount of work on the part of the house keeper. To obviate this difficulty, an alarm device 2 is provided. The alarm device comprises a rectangular shaped casing 3, which casing is detachably secured to a horizontally disposed bottom 4 by means of posts 5. Extending downwardly from the bottom 2 is a U-shaped bracket 6, between the arms 7 of which the upwardly extending flange 8 of the drip pan 1 is received and held by the set screw 9. Arms 7 are spaced from each other a substantial distance, thereby allowing the bead 10 of the flange 8 to be received by the bracket 6 and to allow the reception of different widths of beads, thereby allowing the device to be applied to various types of receptacles. The bracket 6 is located adjacent one end of the bottom 4 of the casing, and the other end extends inwardly over the water 11 within the pan 1. Slidably mounted in a bearing sleeve 12 of the device is a vertically disposed shaft 13, the lower end of which extends through an aperture 14 in the upper side of a float 15 and is held thereon by means of nuts 16 and is air tight by means of the washers 17. The washers 17 prevent passage of air to the chamber 18 or from the chamber 18. The lower end of the float 15 is open thereby allowing air to be cupped in the float 15 and consequently increasing the buoyancy of the float and insuring the tripping of the tripping mechanism hereinafter set forth. The upper end of the shaft 13 is disposed beneath and adjacent the free end 19 of a leaf spring 20, which leaf spring is anchored at 21 to the spring motor plate 22 and is provided with a shoulder 23, which engages over the inwardly extending arm 24 carried on the pivot post 25 and holds the pivot post 25 against oscillation, thereby holding the flapper arm 26 against movement, which flapper arm carries a flapper 27, when oscillated cooperates with the casing 3 for sounding the alarm, that is, the water level within the pan 1 has reached a predetermined point and the pan should be emptied. The oscillation of the striker arm 26 is controlled from a spring motor 28, which rotates the shaft 29, said shaft being provided with a gear 30, which gear meshes with a gear cage 31, carried by a rotatable shaft 32. When the

100
105
110

shaft 32 is rotated a rockable movement is imparted to the shaft 25 by means of a gear 33, with which gear 33 the escapement dog 34, carried by the shaft 25 cooperates. It will be seen that as the dog 34 is oscillated by the gear 33 the strike arm 26 will also oscillate and consequently the alarm will be sounded. When it is desired to render the device inoperative the upwardly extending arm 35, which has its arm 36 pivotally mounted at 37 to the bottom 4, is moved to a position where it will engage the striker arm 26 and hold the same against movement.

From the above it will be seen that a drip pan alarm is provided which is simple in construction, positive in its operation and one which may be easily and quickly attached to conventional forms of drip pans.

The invention having been set forth what is claimed as new and useful is:—

1. The combination with a drip pan, of a level alarm carried thereby, said alarm comprising a horizontally disposed casing, a clamping device adjacent one end of the casing and forming means whereby the device may be attached to the side of the pan, said casing extending inwardly over the pan, a vertically movable float controlled

shaft extending into the casing, and loosely guidable in a bearing thereof, an oscillating striker disposed within the casing, and horizontally disposed a spring motor for oscillating said striker, a shouldered spring cooperating with a portion of the motor for holding the striker against operation, the free end of said shouldered spring being disposed over the upper end of the vertically movable shaft.

2. The combination with a drip pan alarm comprising a spring motor, a horizontally movable and pivotal striker arm, said striker arm being carried by a vertically disposed shaft controlled by the motor, an arm carried by the vertically disposed shaft and horizontally disposed, a shoulder leaf spring overlying the last named arm, of means for actuating the shouldered leaf spring for releasing the striker arm shaft, said means comprising a vertically movable and loosely guidable shaft, the upper end of the shaft being disposed beneath the free end of the leaf spring and a float carried by the vertically movable shaft.

In testimony whereof I have signed my name to this specification.

GEORGE E. ALTMANN.
